(57) **CLAIM**

The ornamental design for a child seat for use with a shopping cart, as shown and described.

DESCRIPTION

FIG. 1 is a front perspective view of my new design for a child seat for use with a shopping cart.

FIG. 2 is a side elevation view of the right side, the left side being a mirror image thereof, of FIG. 1

FIG. 3 is a top plan view of FIG. 1.

FIG. 4 is a bottom plan view of FIG. 1.

FIG. 5 is a front side elevation view of FIG. 1.

FIG. 6 is back side elevation view of FIG. 1.

FIG. 7 is a side elevation view along line 7-7 of FIG. 5.

FIG. 8 is a close up of the locking bar of FIG. 7.

FIG. 9 is a side elevation view of the left side, the right side being a mirror image thereof, of the child seat in the folded position it is in when the carts are nested together.

FIG. 10 is a bottom plan view of FIG. 9; and,

FIG. 11 is a side elevation view of the left sides, the right side being a mirror image thereof, of the seat with the seat back folded down.

The features shown in broken lines in the drawing depict environmental subject matter only and form on part of the claimed design.
